LOCOMOTIVE STOKER

Henry C. Cloyd, Erie, Pa., assignor to The Standard Stoker Company, Incorporated, a corporation of Delaware

Application February 9, 1938, Serial No. 189,491

7 Claims. (Cl. 110—105.5)

This invention relates to stokers of the type delivering fuel to the firing opening of a furnace, and particularly to that portion of a stoker mounted in a locomotive.

In applying a stoker of the type described, it is desirable to locate the lower end of the discharge conduit as close to the under side of the deck as possible, thereby shortening the length of the discharge conduit and thus facilitating the passage of coal therethrough, and also minimizing the angle between the discharge conduit and the conduit leading rearwardly therefrom to the tender, thereby further facilitating passage of fuel through the discharge conduit. The height of the deck with respect to the firing opening varies in different locomotives, so that a different style of discharge conduit would be required for almost every installation in order to maintain the lower end of the discharge conduit uniformly close to the under side of the deck. It is, therefore, an object of this invention to provide a standard style of discharge conduit, so constructed that regardless of variations in the deck height, the lower end of the discharge conduit may be maintained close to the under side of the deck.

Another object of the invention is to provide a novel sectional stoker discharge conduit that is easily and conveniently applied to the locomotive, effects a saving in application cost and reduction in labor.

Still another object of the invention is to provide an improved arrangement for supporting a stoker discharge conduit on a locomotive.

With the above and other objects and advantages in view, the invention consists in the features of construction, the combination of elements and arrangement of parts hereinafter more fully described and claimed, and illustrated in the accompanying drawings, in which

Fig. 1 is a fragmentary longitudinal vertical central section through the rearward portion of a locomotive with the novel stoker discharge casting applied therein and shown in similar section;

Fig. 2 is a sectional view on the line 2—2 of Fig. 1;

Fig. 3 is a sectional view on the line 3—3 of Fig. 1; and

Fig. 4 is a sectional view on the line 4—4 of Fig. 1.

In the drawings, the locomotive is indicated generally by the numeral 10, and it includes a firebox 11 having a backwall 12 with a firing opening 13 therein, a frame 14 and a cab deck 15 extending rearwardly from the backwall 12

below the firing opening 13 and above the frame 14. The firebox 11 is supported at its rearward end on the locomotive frame 14 by means of an expansion plate 16.

5 The stoker is designated generally by the letter S, only so much of it being shown as is essential to a complete understanding of the invention. The stoker S includes a discharge conduit 17 communicating with the lower portion of the firing opening 13 and extending rearwardly and downwardly through an opening 18 in the cab deck 15, and a telescopic conduit section 19, universally connected, as at 20, with the lower rearward end of the discharge conduit 17 and extending rearwardly to the locomotive tender (not shown). A screw conveyor 21 disposed in the telescopic conduit section 19 advances fuel therethrough to the discharge conduit 17. The fuel is forced through the discharge conduit 17 to the firing opening by the pressure of the screw conveyor 21 against the fuel.

The discharge conduit 17 comprises an upper portion 22 and a lower portion 23 hingedly connected together as will be hereinafter described. 25 The upper discharge conduit portion 22 is rigidly secured to the backwall 12 by means of angular brackets 9. A firedoor 8 forms a closure for the upper portion of the firing opening 13.

The lower end of the discharge conduit portion 23 is supported on the locomotive frame 14 by an improved supporting arrangement. The support includes a bracket 24 having a base 25 on which is formed a transversely extending bearing 26. The discharge conduit portion 23 is also provided, at its rearward end, with a depending transversely extending bearing 27. Mounted in and extending beyond the ends of the bearings 26 and 27 are the pintles 28 and 29, respectively. The projecting ends of the pintle 28 are connected with the projecting ends of the pintle 29 by the links 30 and 31; means, such as the pins 7, being provided for securing the links to the pintles. The pintles 28 and 29 are rotatably mounted in the bearings 26 and 27, respectively, providing for relative longitudinal movement between the discharge conduit portion 23 and its support bracket 24.

The base 25 of the support bracket 24 is provided with a longitudinally extending slot 32, and bolts 33 passing through the slot 32 are threaded in the frame 14 for rigidly securing the bracket to the frame. Thus by loosening the bolts 33, the bracket 24 can be moved longitudinally forward or rearward thereby lowering or raising the rearward end of the discharge

conduit portion 23. In this manner the rearward end of the discharge conduit portion 23 can be positioned close to the under side of the cab deck 15 even though the height of the deck above the frame varies with different locomotives.

The base 25 of the support bracket 24 is provided with upstanding longitudinally extending laterally spaced walls 34 and 35, the outer surfaces of which constitute guides for the links 30 and 31, respectively. The links 30 and 31 are disposed closely adjacent the walls 34 and 35 to prevent lateral displacement of the rearward end of the conduit portion 23, sufficient clearance being provided to permit longitudinal pivotal movement of the links.

The upper end of the discharge conduit portion 23 is supported from the boiler mud ring 36. Laterally spaced angular brackets 37 and 38 are rigidly secured with the mud ring 36 and the expansion plate 16 by bolts 39. The firebox 11 is supported at its rear end on the locomotive frame 14 by means of the expansion plate 16, which is of sufficient flexibility to permit slight longitudinal movement of the firebox with respect to the locomotive frame when the firebox expands and contracts. Upstanding rods 40 and 41 having their lower ends threaded, project through the openings 42 and 43, respectively, in the brackets 37 and 38, respectively. Nuts 44 and 45 are threaded on the portion of the rods 40 and 41 projecting beneath the brackets 37 and 38, respectively, and nuts 46 and 47 are threaded on the rods 40 and 41 above the brackets 37 and 38, respectively. The rods 40 and 41 are thus vertically adjustable and are held firmly in adjusted position by drawing up the lock nuts 46 and 47 tightly against the brackets 37 and 38, respectively. The rods 40 and 41 provide a support for the adjacent ends of the discharge conduit portions 22 and 23, thereby relieving the backhead of a part of the weight of said conduit portions. Because of their length, the rods 40 and 41 will flex sufficiently to compensate for the uneven expansion and contraction of the backwall 12 adjacent the upper and lower ends of the rods 40 and 41.

The bottom wall of the discharge conduit portion 23 is provided at its forward end with a forwardly projecting transversely extending bearing member 48 received between bearing members 49 and 50 projecting rearwardly from the bottom wall of the discharge conduit portion 22. A pintle 51 passes through the bearing members 48, 49 and 50 for hinging the discharge conduit portion 23 to the discharge conduit portion 22. The upper ends of the rods 40 and 41 are provided with transversely extending bearing members 52 and 53, respectively, receiving the ends of the pintle 51, which is locked in position by pins 54 and 55, passing through the bearing members 52 and 53, respectively, and the pintle 51.

The rearward end of the discharge conduit portion 22 is provided with an internal circumferentially extending recess 56 receiving the upper forward end of the discharge conduit portion 23, providing for pivotal movement of the portion 23 within the portion 22 about the pintle 51 as an axis. A strip of spring steel 57, suitably fastened to the upper forward end of the discharge conduit portion 23 and overlapping the inner surface of the discharge conduit portion forms a coal tight seal.

Fuel discharged from the conduit 17 is received on the fuel supporting surface of a distributing

plate 58, preferably of the type having separable front and rear sections 70 and 71, respectively. The construction of the distributing plate forms no part of this invention and is, therefore, not described in detail. The front section 70 is seated on ledge-like means 72 extending forwardly of and below the level of the upper surface of the rear section 71. A hook 73 extends rearwardly of the front section 70 beneath the level of the upper surface thereof and engages the underside of the rear section 71 preventing downward displacement of the front section by reason of the weight of that portion overhanging the ledge-like means 72. Additional securing means, such as pin means 74, extends through the rear section 71 and the hook 73. The rearward end of the distributing plate 58 is received in a recess 59 formed in the forward end of the bottom of the discharge conduit portion 22. Suitable means, such as bolts, (not shown) passing through the depending flange 60 of the plate 58 is provided for securing the plate to the discharge conduit portion 22. A pressure fluid distributor head 61 is positioned at the rear of the plate 58, from which head blasts of pressure fluid are emitted through the jet openings 62 sweeping across the fuel distributing plate 58 and projecting the fuel over the fire in the firebox.

Mounted adjacent the side walls of the discharge conduit portion 22 and rearward of the distributor head 62 on vertical pivot pins 63 and 64 are the guide vanes 66 and 65, respectively. The vanes 66 and 65 extend forward of the distributor head 62 and are movable about the pivot pins 63 and 64, respectively across the distributing plate 58 to deliver more fuel to one side or the other of the plate.

From the above description it is clear that the present invention simplifies application of a stoker to a locomotive. The upper portion 22 of the discharge conduit can be properly located and fixed in position, and the correct relation thereof with the distributing table and distributor head can be provided without the necessity of moving the bulky lower portion 23 of the discharge conduit.

I claim:

1. In a locomotive having a frame and a boiler provided with a firebox having a backwall with a firing opening therein, the combination with said backwall and frame of a stoker fuel discharge conduit extending upwardly and forwardly to said firing opening, said fuel discharge conduit comprising separable upper and lower portions hingedly connected at their adjacent ends, said upper portion being rigidly secured with respect to said backwall, and means extending between said frame and said conduit for vertically supporting the entire weight of said lower conduit portion on said frame, said means including a support member mounted on said frame and having a connection with said lower conduit portion rearward of its center of gravity and an additional support member rearward of said backwall connected with said frame and having a connection with said lower conduit portion forward of its center of gravity, each of said support members having a hinged connection with said lower conduit portion for vertical swinging movement of said conduit portion.

2. In a locomotive having a frame and a boiler provided with a firebox having a backwall with a firing opening therein, the combination with said backwall and frame of a stoker fuel dis-

charge conduit extending upwardly and forwardly to said firing opening, said fuel discharge conduit comprising separable upper and lower portions hingedly connected at their adjacent ends, said upper portion being rigidly secured with respect to said backwall, and means extending between said frame and said conduit for vertically supporting the entire weight of said lower conduit portion on said frame, said means including a support member mounted on said frame and having a connection with said lower conduit portion rearward of its center of gravity and an additional support member rearward of said backwall connected with said frame and having a connection with said lower conduit portion forward of its center of gravity, each of said support members having a hinged connection with said lower conduit portion for vertical swinging movement of said conduit portion, said support members being adjustable for raising and lowering the respective ends of said lower conduit portion to any one of a number of positions.

3. In a locomotive having a frame and a firebox, the combination with said frame and firebox of a stoker fuel delivery conduit inclined toward the firebox, support means rearward of said firebox extending downwardly from a position on said conduit forward of its center of gravity to said frame, said support means including a pivotal connection with said conduit for movement of said conduit about a horizontal transverse axis, and support means extending downwardly from a position on said conduit rearward of its center of gravity to said frame, said last named support means being adjustable to any one of a number of positions on said frame for raising and lowering said conduit about said pivotal connection, and said last named support means including a pivotal connection with the conduit.

4. In a locomotive having a frame and a firebox, the combination with said frame and firebox of a stoker fuel delivery conduit inclined toward the firebox, support means rearward of said firebox extending downwardly from a position on said conduit forward of its center of gravity to said frame, said support means being adjustable for raising and lowering the upper forward end of said conduit and including a pivotal connection with said conduit for movement of said conduit about a horizontal transverse axis, and support means extending downwardly from a position on said conduit rearward of its center of gravity to said frame, said last named support means being adjustable to any one of a number of positions on said frame for raising and lowering said conduit about said pivotal connection, and said last named support means including a pivotal connection with the conduit.

5. In a locomotive having a frame and a boiler provided with a firebox having a backwall with

- a firing opening therein, the combination with said backwall and frame of a stoker fuel delivery conduit extending upwardly and forwardly to said firing opening, said conduit including separable upper and lower portions, said upper portion being rigidly secured to said backwall, said portions along a part of their adjacent ends having means forming a hinge for vertical swinging movement of said lower portion, and means extending between said frame and said lower conduit portion for supporting the entire weight of said lower conduit portion on the locomotive frame, said support means including adjustable means for raising and lowering one end of said lower conduit portion about its other end.
6. In a locomotive having a frame and a boiler provided with a firebox having a backwall with a firing opening therein, the combination with said backwall and frame of a stoker fuel delivery conduit extending upwardly and forwardly to said firing opening, said conduit including separable upper and lower portions, said upper portion being rigidly secured to said backwall, said portions along a part of their adjacent ends having means forming a hinge for vertical swinging movement of said lower portion, means extending between the hinged ends of said conduit portions and said frame for supporting the adjacent ends of said conduit portions on said frame, and means extending between the lower rearward end of said lower conduit portion and said frame for supporting the lower rearward end of said lower conduit portion on said frame, said last-named support means being adjustable for raising and lowering said lower conduit portion about its hinged end.
7. In a locomotive having a frame and a boiler provided with a firebox having a backwall with a firing opening therein, the combination with said backwall and frame of a stoker fuel delivery conduit extending upwardly and forwardly to said firing opening, said conduit including separable upper and lower portions, said upper portion being rigidly secured to said backwall, said portions along a part of their adjacent ends having means forming a hinge for vertical swinging movement of said lower portion, the free part of the hinged end of one of said conduit portions telescoping the free part of the hinged end of the other of said conduit portions, means extending between the hinged ends of said conduit portions and said frame for supporting the adjacent ends of said conduit portions on said frame, and means extending between the lower rearward end of said lower conduit portion and said frame for supporting the lower rearward end of said lower conduit portion on said frame, said last-named support means being adjustable for raising and lowering said lower conduit portion about its hinged end.

HENRY C. CLOYD.
